(57) **CLAIM**

The ornamental design for a vial holder as shown and described.

DESCRIPTION

FIG. 1 is a front perspective view of a vial holder showing my new design;

FIG. 2 is a rear perspective view thereof;

FIG. 3 is a bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is another front perspective view showing a key ring coupled thereto; and,

FIG. 11 is the other front perspective view showing the key ring and a vial coupled thereto.

The dashed lines showing a key ring and a vial in FIGS. 10-11 depict environmental subject matter and form no part of the claimed design. The remaining dashed lines in the drawings depict portions of the vial holder that form no part of the claimed design. The dot-dash broken lines in FIGS. 1-8 and 10-11 represent unclaimed boundary lines and form no part of the claimed design.
